UNITED STATES PATENT OFFICE.

WILLIAM A. KIRBY, OF AUBURN, NEW YORK.

MOWING-MACHINE.

SPECIFICATION forming part of Letters Patent No. 245,637, dated August 16, 1881.

Application filed April 19, 1881. (No model.)

To all whom it may concern:

Be it known that I, WILLIAM A. KIRBY, of Auburn, in the county of Cayuga and State of New York, have invented certain Improvements in Mowing-Machines, of which the following is a specification.

This invention relates to that well-known type of two-wheeled front-cut machines commonly known as "Kirby mowers," wherein the 10 cutter-frame and the devices employed in immediate connection therewith are connected with the main axle of the machine by a main frame arranged to swing upon the axle, and jointed at its forward end to the cutter-frame, 15 and in which a seat is used in connection with the frame in such manner that the weight of the rider serves to counterbalance the weight of the cutter-frame.

The present improvements consist, mainly, in 20 the peculiar construction and arrangement of the parts for turning the finger-bar up end-wise; in adjustable connecting devices between the cutter-frame and its regulating-lever; in a loose connection between the cutter-frame 25 and the lever, by which the finger-bar is rolled or tipped to vary the height of the fingers; in the combination of a spring with the counter-balancing-seat; in the peculiar manner of applying said spring; and in other details, which 30 will be hereinafter fully explained.

Referring to the accompanying drawings, Figure 1 represents a side elevation of my machine, the wheel on the outer or cutting side of the machine being removed and the main 35 shoe being shown in cross-section. Fig. 2 is a vertical central section through one of the driving-wheels and its axle, illustrating the manner in which the wheel is constructed and attached. Fig. 3 is a detail view, illustrating 40 the manner in which the spring is connected to the seat-standard and the supporting devices. Fig. 4 is a top-plan view of the machine. Fig. 5 is a cross-section on the line $x-x$, Fig. 4, looking forward, the finger-bar being shown in 45 a partially raised position. Fig. 6 is a similar view with the finger-bar in its operative position. Fig. 7 is a top-plan view of the cutter-frame; Fig. 8, a view of the forward end of the same.

50 A A represent the two main wheels of the machine, mounted upon and sustaining oppo-

site ends of the main axle B, and provided with internal geared rims, from which motion is transmitted to the driving-gear of the machine.

C represents the main or connecting frame 55 of the machine, having its arms fastened rigidly at the rear end to the main axle, and jointed at its forward end to the rear end of the cutter-frame D, to which latter the finger-bar E is attached.

F represents the draft-pole or tongue of the 60 machine, pivoted to the cutter-frame and connected with a hand-lever, H, by means of which the relative positions of the finger-bar, the tongue, and the main frame are regulated. 65

In their general construction and mode of operation the above parts resemble those of the ordinary and well-known Kirby machines, the main frame C forming a jointed connection by which the front or cutter frame is carried, 70 while at the same time it permits the cutter-frame to rise and fall, in order to follow the surface of the ground.

The main wheels A are made of cast-iron, and 75 have their hubs formed each with a radial flange, a, around its inner end. The hubs are slipped loosely upon and cover the end of the axle, and each hub is held in place upon the axle by means of a plate, b, bolted or otherwise secured to the main frame, and arranged to engage over the flange of the hub in the manner clearly represented in Fig. 2. By thus constructing the parts I am enabled to use a shorter axle than usual, to have the outer end of the hub closed, in order to exclude dirt and sand 85 from the wearing-surfaces, and to secure the wheel upon the axle at much less cost than by the ordinary construction.

The plate b should be so constructed as to 90 cover and close the upper side of the hub, in order to serve as a guard to prevent the entrance of sand and dust at the inner end of the hub.

Referring, now, to the construction of the frame, it will be seen that the front or cutter 95 frame, D, is jointed to the rear or main frame, C, by or on a line with the transverse shaft L, the ends of which are provided with pinions gearing into the main wheels A, motion being transmitted from the shaft through intermediate gearing to the cutter bar or knife in the ordinary or any other suitable manner. The 100

frame D has its main portion cast in one piece, with a sleeve, *d*, fitted upon the shaft L, and with a forwardly-extending arm, *e*, adapted to sustain the main crank-shaft M, from which the cutter is driven.

N represents the inner or main shoe, to which the heel of the finger-bar is secured. This shoe is carried by horizontal pivots *o*, in order that the bar may swing upward at its outer end, as usual, the pivots *o* being sustained by castings secured to the ends of two flat bars, *p* and *q*, extending laterally from and secured firmly to the frame D. The bars *p* and *q* are formed by cutting them of proper length from flat bars 15 iron and punching holes in their ends to receive fastening-bolts. The bars are seated at one end firmly in seats or sockets formed on the frame D, and are secured thereto by fastening-bolts, while at the opposite ends they are 20 inserted and secured in like manner in sockets on the castings which support pivots *o*. These shoe-supporting bars *p* and *q* are braced and held in position by means of a longitudinal bar, *f*, extending forward from the sleeve *d* of frame D to the casting which carries the forward shoe-pivot, the ends of this bar being seated and bolted firmly in sockets.

As shown in the drawings, the bar *f* is connected firmly to the bars *p* and *q* at the points 30 where they cross by means of castings *m* and *h*. The bar *f*, thus applied, serves as a brace to hold the bars *p* and *q* and the main shoe firmly in position.

It will of course be understood that the 35 bars *p*, *q*, and *f* are secured rigidly to the front frame, D, and form a part thereof.

The draft-pole or tongue F is bolted firmly to a casting, K, of the form shown in the drawings, this casting being connected by a pivot-bolt, *l*, to the casting *h* on the front of frame D, and extending thence backward beyond the tongue, where it is connected by a link, O, to a hand-lever, H, this lever being pivoted at 40 s to an upright notched segment, *t*, secured rigidly upon the bar *f* of frame D, or otherwise rigidly secured to said frame.

By means of the hand-lever the position of the tongue and the cutter-supporting frame D may be varied in such manner as to effect 50 the raising or lowering of said frame and the main shoe in substantially the same manner as in the ordinary Kirby machine.

The link O is adjustably connected to the tongue-plate K in the manner represented in 55 Fig. 1, the link being provided with a number of holes at different heights, to receive a connecting pin or pivot, *w*, so that by changing the pin from one hole to another the height of a link may be varied for the purpose of causing the main shoe to be carried at any height required. The link O has its upper end slotted, and connected to the lever H by a pin or journal passing through said slot. Under this construction the descent of the link and cutter-frame is limited by the upper end of the slot encountering the connecting-pin; but at

the same time the shoe and cutter-frame are permitted to rise freely whenever an obstruction or elevation is encountered. This vertically-adjustable slotted link, by which the height of the cut is regulated, forms an important feature of my present invention. While it is preferred to adhere to the form of link shown in the drawings, it is obvious that it may be changed in form and in its manner of attachment, provided the mode of action is not departed from.

For the purpose of preventing lateral play of the tongue, and of giving greater rigidity, the tongue-plate K is provided with a lip, *y*, 80 arranged to engage over and slide upon a rib or flange on the casting *m* of frame D, as clearly represented in Figs. 1 and 4.

The hand-lever H is provided, as usual, with a locking device, *a'*, engaging with the notched 85 plate *t*, to fasten the lever firmly in position.

For the purpose of regulating the height of the rear end of frame D and the main shoe, in order to tip the finger-bar upward or downward at the front, a hand-lever, P, is mounted 90 upon the rear frame, C, as shown in Figs. 1 and 4, and connected by a slotted link, Q, with the rear end of frame D, at a point in rear of that at which the frames C and D are jointed together. Lever P is mounted upon a notched 95 plate or segment, *b'*, and provided with a locking device to engage therewith and hold the lever in position. By throwing the lever P backward the rear end of the frame D may be raised to any desired elevation and suspended 100 at that point, the slotted link, however, permitting the frame to rise freely in passing over obstructions.

The adjustable slotted connection between the frames C and D, as above described, forms 105 another important feature of my present invention.

For the purpose of carrying on or assisting to carry the main shoe N, I make use of a caster-wheel, T, located at the front of the machine, 110 at the forward end of a bar, U, in substantially the same manner as in certain machines hitherto patented to me. The wheel T has its frame or carrying-post swiveled to the forward end of the bar U, or a casting thereon, in advance of the main shoe, the bar U being extended thence backward, and connected by a pivot-bolt, *c*, to the casting at the heel of the runner. The bar U is connected by a key or pin to the casting *h* at the forward end of the 115 main shoe, the casting being provided, as shown in Fig. 1, with a series of holes for the pin, to admit of the shoe being adjusted vertically with reference to the bar and caster-wheel.

For the purpose of turning the finger-bar E upward at its outer end, either to pass obstructions or to throw it out of action, I provide a lever, V, pivoted to the casting *m* at the heel of the shoe, and arranged to bear at one end 120 upon a shoulder, *d'*, on the main shoe N, as shown in Figs. 1, 4, 5, and 6, and connected at

its opposite end by a link, W, to the hand-lever H, the link being connected to the lever ordinarily by the same pivot which connects the lever to the lifting-link O, heretofore described.

5 Under the above arrangement of parts a backward movement of the lever H causes the link O to elevate the front frame and shoe, and at the same time causes the link W to operate the lever V, the latter, in turn, acting 10 upon the shoe N, in the manner represented in Fig. 5, causing the same to swing upward with the finger-bar.

X represents the driver's seat, mounted upon the rear end of an arm or standard, Y, the 15 standard being supported upon the axle, and connected at its forward end with the front frame, D, so that the weight of the driver serves to counterbalance to an extent the weight of the front frame, as in the ordinary 20 Kirby machine.

Hitherto it has been the practice to sustain the lever upon a rigid support on the axle or the rear frame, and to establish a direct and solid connection between the seat and the front 25 frame, the effect of which was to cause a severe and disagreeable jolting or straining of the machine when operated on rough ground. To overcome this difficulty I now interpose between the seat and its support a spring, this 30 spring serving as a yielding connection between the parts, and tending to prevent the violent shocks and strains which are commonly transmitted from the front frame to the seat, thus causing the machine to travel more easily 35 and with less wear than heretofore.

It is preferred to apply the spring in the manner shown in the drawings; but it may be varied in form and attachment, provided it retains substantially the mode of action above 40 described.

As shown in the drawings, the seat support or standard Y is connected at its forward end to the frame D by means of a link, e', and sustained near its middle by the semi-elliptical 45 or C-shaped spring Z, the spring being connected at its upper end by a pivot to a plate on the under side of the support Y, and being connected at the lower end by a pivot, f', to ears g', formed on the frame C. The frame C 50 is provided with a series of holes for the pivot-pin, to admit of the same being adjusted forward and backward; and the plate of the support Y is in like manner provided with a series of holes, to admit of the spring-connecting devices being adjusted forward and backward 55 thereunder.

It will be seen that the seat-support sustained upon the spring Z, in the manner above described, carries the rider with an easy yielding 60 motion, and that in the event of the front frame encountering sudden or violent resistance the spring will yield and gradually overcome the shock. The forward and backward adjustment of the spring permits the machine to be adapted 65 for riders of different weights.

I do not claim, broadly, a mower-seat sustained upon a spring; but I believe myself to be the first to apply a spring to sustain a seat-support which is arranged in the peculiar connection or combination herein shown.

I am aware that drivers' seats arranged to partially counterbalance the weight of the main frame have been employed in mowers; and, also, that a seat-supporting lever connected with the main frame and the front of the machine 70 has been sustained by means of a spring.

My invention is restricted to a seat arranged in the combination herein shown, and sustained by a spring, substantially as represented.

Having thus described my invention, what 80 I claim is—

1. In combination with the axle, the frame C and frame D, the pivoted tongue F, and the lever H, the latter united to the tongue by means of a slotted or yielding connection, substantially as described.

2. In combination with the tongue F and frame D, arranged to operate as described, the lever H, and the link O, having a slotted connection with the lever, and having its lower 90 end adjustably connected with the tongue.

3. In combination with the mower, frame D, and pivoted tongue F, arranged and operating as described, the hand-lever H, and link O, provided in its upper end with a slot, and in its 95 lower end with a series of holes, substantially as and for the purpose described.

4. In a mower of the type herein described, the combination of the frame C, frame D, and adjusting-lever P, the latter connected with 100 frame D by a connection free to yield in an upward direction.

5. The combination of the frames C and D, lever P, with devices for locking the same, and slotted link Q.

6. In combination with the frame D and tongue F, the hand-lever H, having a slotted connection with the tongue and a positive connection with the lever by which the finger-bar is tipped or swung upward.

7. The combination of the wheeled main axle, the main frame journaled thereon, a cutter-frame journaled to the front of the main frame, and the seat-sustaining lever Y, sustained by a spring-support on the main frame and jointed 115 at its forward end to the cutter-frame, substantially as shown.

8. In combination with the main axle and the frames C and D, the seat-supporting bar Y, and a sustaining-spring, Z, located beneath bar Y, and sustained upon frame C or upon the axle.

9. In combination with the front frame D, and seat-support Y connected therewith, the spring Z, adjustably connected to the support 125 Y and to the frame C.

WILLIAM A. KIRBY.

Witnesses:
